UNITED STATES PATENT OFFICE.

FOSCOLO O. HENDRICK, OF EAST ORANGE, NEW JERSEY, ASSIGNOR TO PULLCLEAN MANUFACTURING CO., INC., OF NEW YORK, N. Y., A CORPORATION OF NEW YORK.

ROLLER-TOWEL CABINET.

1,297,688.

Specification of Letters Patent. Patented Mar. 18, 1919.

Application filed April 11, 1916. Serial No. 90,330.

To all whom it may concern:

Be it known that I, FOSCOLO O. HENDRICK, citizen of the United States, and resident of East Orange, in the county of Essex and State of New Jersey, have invented certain new and useful Improvements in Roller-Towel Cabinets, of which the following is a specification.

My invention relates to roller towel cabinets of the general type disclosed in Letters Patent No. 1,050,539, granted to me January 14, 1913, and has particular reference to a coin-controlled mechanism forming part of such a cabinet for regulating the supply of toweling that may be withdrawn from the cabinet for use.

The cabinet of my aforesaid patent comprises a series of rollers, one of which is a supply-roller for carrying a roll of toweling from which a clean supply or length of toweling may be drawn as required for use, and another of which is a take-up roller adapted to take up the soiled toweling at substantially the same rate as that at which the clean toweling is drawn from the supply-roller; this take-up roller being operated by means of a third roller, termed an "operating roller", which is rotated by the frictional engagement therewith of the toweling as the latter is drawn from the supply roller and which imparts such rotative movement to the take-up roller through suitable gearing.

My present invention has for its object to provide a simple and efficient coin-controlled mechanism for regulating the supply of toweling that may be drawn from a cabinet of the type referred to. In accordance therewith, I provide a mechanism for normally locking certain of the towel engaging rollers and thereby the toweling, against feeding or delivery movement, and which mechanism is rendered operative to release the rollers and permit a feeding or delivery movement of the toweling only by the insertion of a coin at the proper point in the mechanism.

Referring now to the accompanying drawings—

Figure 1 is a sectional side elevation of a cabinet embodying my invention, the section being taken vertically through the cabinet adjacent one side thereof.

Fig. 2 is a similar view of part of the

mechanism, showing a different position of 55 certain of the movable parts.

Fig. 3 is an enlarged sectional detail showing the passage of the coin through the machine and its coöperation with certain of the operating parts thereof.

Similar reference characters indicate like parts in the several figures of the drawings.

The several operating parts constituting my improved device may be mounted upon a frame or support of any suitable kind, and are contained within an inclosing casing or cabinet, such as indicated at 2.

The main frame or support for the operating parts comprises a pair of duplicate side brackets 3 (only one of which is here shown) 70 connected by suitable tie-rods, such as 4. Supported at their opposite ends by these side brackets 3 are a series of rollers, the uppermost of which, indicated at 5, is the so-called supply-roller carrying a roll of toweling, 75 such as t, from which the toweling is adapted to be drawn as required for use. From this roller 5 the toweling, as indicated by the dot-and-dash line, is passed forwardly over a guide roller 6, then backwardly to 80 and about a roller 7, and from thence forwardly over a guide-rod 8 and on through an opening 9 in the wall of the cabinet to a guide-roller 10 at the front side of the latter, from which it drops in a convenient position 85 for use as shown.

A pair of rollers, indicated at 11 and 12, operate to engage therebetween the soiled end of the toweling, which is led to them through an opening in the wall of the cabinet as shown, and take up the same at substantially the same rate as that at which the clean toweling is drawn from the supply-roller 5, whereby a substantially constant 90 length of toweling in loop form is maintained for use at the front or exterior side of the cabinet. Such operation of the take-up rollers 11 and 12 is effected by means of the roller 7, termed by me the "operating roller", which is rotated by the frictional en-

gagement therewith of the toweling as the latter is withdrawn from the supply-roller, and which imparts such rotative movement to the take-up roller 11 through suitable motion-transmitting means, such as the 95 sprocket-chain connection diagrammatically indicated at 13. The rotative movement 100 thus imparted to the take-up roller 11 causes

it to coöperate with the opposing roller 12 and take up the soiled end of the toweling by drawing it therebetween. When the soiled end of the toweling is thus taken up 5 by the take-up roller, it may be deposited in the cabinet in any desired manner, that is, after being drawn between the rollers it may be deposited loosely in the cabinet, or it may be wound directly upon one of the take-up 10 rollers. The latter is the preferable way and the way here shown. When the toweling is wound upon one of the take-up rollers, one of the latter should be yieldingly supported relative to the other in order to accommodate the increasing thickness of the 15 toweling as it is wound on the roller. To provide for this, the roller 11 is carried at each end by a link 14 which is supported to turn about the axis of the roller 7 and connected at its lower end with a coiled spring 15 which acts to yieldingly hold the roller 11 against the roller 12. As a means for 20 steadyng and guiding the roller 11 when being moved about the axis of the roller 7, 25 its end journals project through segmental slots 16 in the side brackets of the frame, as shown.

In order to assure a more positive coöperation between the toweling and the rollers, 30 whereby undue slippage between them will be avoided, certain of the rollers, particularly those indicated at 6, 7, and 11, are provided with a roughened surface, which may be produced by covering them with sand 35 paper.

Having now described the towel supplying and take-up means in sufficient detail for the purposes of my present invention, I will next describe the coin-controlled mechanism for regulating the operation of said 40 means. This comprises a pinion gear 20 fixed to one end of the operating roller 7 and meshing with a large gear wheel 21 which is mounted on a stationary bearing 22 and 45 provided with a pin or projection 23 for engagement with a pivoted detent 24, as shown in Fig. 1, by which the said gears and connected roller 7 are locked against rotation in that direction permitting of the 50 toweling being drawn off from the supply roller 5. The detent 24 is mounted on a stationary bearing 25 and is provided with an extension 26 having notches 27 therein, one of which is adapted to be engaged by the 55 end of the spring 28 for movably holding the detent in its normal locking position of engagement with the pin 23 on the gear wheel 21, as shown in Fig. 1.

The means for moving the said detent 60 from locking to releasing position, whereby to permit withdrawal from the cabinet of a predetermined length of toweling, comprises a frame 29, here shown as formed of two plates secured together in spaced relation by suitable fastening means, such as the

screws 30, and attached to the cabinet casing by suitable fastening means, such as the screws 31. This frame is provided with a coin-receiving slot 32 opening at the front side of the cabinet and leading downwardly 70 between two levers 33 and 34 which are pivoted between the oppositely located plates of the frame 29, at 35 and 36 respectively. The lever 33 is of greater length than the lever 34 and extends above the frame 29 75 where it is connected through a link 37 with a plunger 38 which is slidably mounted in a bearing 39 with its front end projecting beyond the front wall of the cabinet as shown. The lever 34 is connected by a pin 80 40 extending through a slot 41 in the wall of the frame 29, with the vertical arm 42 of a bell-crank lever which is mounted on the outer wall of the frame 29 to turn about the axis of the lever 34. The horizontal arm 43 85 of this bell-crank lever engages at its end with a trip lever 44, which is mounted on the bearing 25 supporting the detent 24 and provided with an arm carrying an adjustable screw 45 for engagement with a lip 46 90 on the detent 24. A coiled spring 47 arranged with one end engaging the trip lever and its opposite end engaging a fixed part 48 of the frame, acts to yieldingly hold said trip lever in a normal position with an adjustable stop thereon, in the form of a screw 49, in contact with a stationary stop, here shown as the said frame part 48. In this position of the trip lever, the detent may assume its normal locking position as shown 100 in Fig. 1.

With the construction and arrangement of parts shown, the operation of effecting a release of the towel engaging rollers to permit of the withdrawal from the cabinet of 105 a clean length of toweling is as follows: A coin of the proper size and denomination is inserted into the slot 32 and drops down between the levers 33 and 34 until it comes to a rest on a stop-wall 50, as shown in Fig. 3, 110 in which position it bridges the space between said levers and provides a connection between them. The plunger 38 is then pressed inwardly, thereby swinging the levers 33 and 34 about their axes as indicated by dotted lines in Fig. 3, which movement of the lever 34 operates the connected bell-crank lever 42-43 to cause it to depress the trip lever 44, which movement of the latter swings the detent 24 backward to releasing position, as shown in Fig. 2, where it is temporarily held by the engagement of the spring 28 in the lower of the notches 27. After such release of the towel pulling mechanism, the exposed length of towel may 115 be pulled upon to withdraw from the cabinet a clean length of towel. This pulling of the towel will of course effect a rotation of the several rollers and connected gear wheels in the manner before described, and 120 125 130

after the gear wheel 21 has made a partial revolution, the detent pin 23 thereon will engage an arm 51 of the pivoted detent lever 24 which extends across its path, as shown in Fig. 2, and operate the same to return the detent to its normal position for engagement with the pin 23. A continued withdrawal of the towel may take place until the gear wheel 21 has made a complete revolution and its pin 23 has again been brought into locking engagement with the detent 24; whereupon the further withdrawal of the toweling is stopped.

When the levers 33 and 34 have been moved to the dotted line position shown in Fig. 3, they will have carried the coin laterally beyond the stop-wall 50 to a point in line with an off-set extension 52 of the coin slot 32, where it will be discharged from between the engaging levers and drop into a suitable receptacle (not shown) for receiving the same. Following such discharge of the coin and the release of the plunger 38, the latter and connecting lever 33 will be returned to their normal positions by suitable means, here shown as a spring 53 connecting at one end with a stationary part 54, and at its opposite end with the upper end of said lever. The lever 34 and connecting bell-crank 42-43 are also returned to their normal positions at the same time by suitable means, here shown as a spring 55 supported with one end engaging a stationary part 56 and its opposite end engaging the bell-crank at 57.

If the coin inserted into machine is too small to properly bridge the space between the two levers 33 and 34, the lever 34 will not have a sufficient movement imparted to it to shift the detent to releasing position, and consequently a delivery of the towel will not be permitted.

What I claim is:—

1. In a roller towel cabinet, and in combination, a roller for engaging the towel and controlling its delivery from the cabinet, a rotary member geared to said roller, a detent pin on said rotary member, a pivoted detent lever provided with an abutment for engagement with said detent pin to normally lock said roller against towel delivery movement, a trip lever movable relative to said detent lever and adapted when depressed to engage said detent lever and release the abutment thereon from said detent pin to permit rotation of the roller, and means for depressing said lever.

2. In a roller towel cabinet, and in combination, a roller for engaging the towel and controlling its delivery from the cabinet, a rotary member geared to said roller, a detent pin on said rotary member, a pivoted detent lever having an abutment for engagement with said detent pin to normally lock said roller against towel de-

livery movement, a trip lever separate from and pivoted co-axially with said detent lever, means carried by the trip lever adapted when depressed to engage said detent lever, an arm on said detent lever adapted to be engaged by said detent pin to return the detent lever to its normal position, means for depressing said trip lever, and means for returning said trip lever to normal position.

3. In a roller towel cabinet, and in combination, a roller for engaging the towel and controlling its delivery from the cabinet, a rotary member geared to said roller, a detent pin on said rotary member, a pivoted detent lever provided with an abutment for engagement with said detent pin for normally locking said roller against towel delivery movement, an arm carried by said detent lever adapted to be engaged by said detent pin upon rotation of said rotary member to return the detent lever to its normal position, an extension on said detent lever having a pair of notches in one of its edges, a spring having its free end adapted to engage in said notches, a trip lever separate from said detent lever and adapted when depressed to engage said detent lever to throw the abutment thereon away from said detent pin, and means for depressing said trip lever.

4. In a roller towel cabinet, and in combination, a roller for engaging the towel and controlling its delivery from the cabinet, a rotary member geared to said roller, a detent pin on said rotary member, a pivoted detent lever provided with an abutment for engagement with the detent pin to normally lock said roller against towel delivery movement, an arm carried by said detent lever adapted to be engaged by said detent pin upon rotation of the rotary member to return the detent lever to its normal position, a trip lever pivoted co-axially with and movable relative to said detent lever, an adjusting screw carried by said trip lever and adapted to engage said detent lever for releasing the abutment from said detent pin, a spring for normally returning said trip lever to normal position, and means for depressing said trip lever comprising two normally disconnected members, means for guiding a coin between said members whereby to operatively connect the same, and means for operating said members when so connected.

5. In a roller towel cabinet, the combination with a roller for engaging the towel and controlling its delivery from the cabinet, of a coin-controlled mechanism for regulating the delivery movement of said roller, comprising a rotary member geared to said roller, a detent normally engaging said rotary member to lock it and the connected roller against delivery movement, a

4
trip lever movable relative to and adapted to coöperate with said detent, a bell-crank lever having one end adapted to engage said trip lever, a pair of normally disconnected levers for operating said trip device, a connection between the other arm of said crank lever and one of said last mentioned levers, a chute for guiding a coin between said disconnected levers whereby to operate 10 tively connect the same, a push rod for operating said levers when so connected to actuate the trip device, means for return-

ing said disconnected levers and handle to normal position, and means operated from said roller when rotated by the delivery of 15 the towel from the cabinet for restoring the detent to locking position.

Signed at New York in the county of New York and State of New York this sixth day of April A. D. 1916.

FOSCOLO O. HENDRICK.
